Herman Miller, Inc., Zeeland, Mich., a corporation of Michigan

Filed Feb. 5, 1962, Ser. No. 68,653

Term of patent 14 years

(Cl. D92—1)

The FIGURE is a plan view of a textile fabric, showing my new design. The design unit is contained within the dot-and-dash lines, which unit is repeated in regular succession, as indicated by the extensions beyond the unit boundaries.

The drawing is lined to indicate color.

I claim:

The ornamental design for a textile fabric, as shown and described.
